DESIGN FOR A BOTTLE

Louis Borokoff, Brooklyn, N. Y.

Application May 28, 1932. Serial No. 43,924

Term of patent 14 years

To all whom it may concern:

Be it known that I, LOUIS BOROKOFF, a citizen of the United States of America, and a resident of Brooklyn, county of Kings, and State of New York, have invented a new, original, and ornamental Design for a Bottle, of which the following is a specification, reference being had to the accompanying drawing, forming a part thereof.

I claim

The ornamental design for a bottle, as shown.

LOUIS BOROKOFF.
